US00D908212S

(12) **United States Design Patent** (10) **Patent No.:** **US D908,212 S**
(45) **Date of Patent:** **** Jan. 19, 2021**

(54) **ADAPTER**

(71) Applicant: **Kristine Marie Taylor**, Redwood City, CA (US)

(72) Inventor: **Kristine Marie Taylor**, Redwood City, CA (US)

(**) Term: **15 Years**

(21) Appl. No.: **29/614,168**

(22) Filed: **Aug. 16, 2017**

Related U.S. Application Data

(63) Continuation-in-part of application No. 15/530,694, filed on Aug. 17, 2016, now abandoned, and a continuation-in-part of application No. 15/530,693, filed on Aug. 19, 2016, now abandoned.

(57) **CLAIM**

The ornamental design for an adapter, as shown and described.

DESCRIPTION

FIG. 1 is a perspective top view of an adapter of the present invention;

FIG. 2 is a perspective bottom view of the adapter of FIG. 1;

FIG. 3 is a top view of the adapter of FIG. 1;

FIG. 4 is a bottom view of the adapter of FIG. 1; and,

FIG. 5 is a side view of the adapter of FIG. 1.

The dash-dot-dash lines indicate boundaries of the adapter that form no part of the claim.

1 Claim, 5 Drawing Sheets
